US00D661667S

(12) **United States Design Patent**
Heng et al.

(10) **Patent No.:** **US D661,667 S**
(45) **Date of Patent:** **** Jun. 12, 2012**

(54) **SOCKET ASSEMBLY**

(75) Inventors: **Stephen Heng**, Los Gatos, CA (US);
Mahesh Hardikar, San Jose, CA (US);
Ali Hassanzadeh, Fremont, CA (US);
Sanjay Dandia, San Jose, CA (US)

CLAIM

The ornamental design for a socket assembly, as shown and described.

DESCRIPTION

FIG. 1 is a first front perspective view of the socket assembly;
FIG. 2 is a first front view of the socket assembly;
FIG. 3 is a first top view of the socket assembly;
FIG. 4 is a first bottom view of the socket assembly;
FIG. 5 is a first left side view of the socket assembly;
FIG. 6 is a first right side view of the socket assembly;
FIG. 7 is a first rear view of the socket assembly;
FIG. 8 is a second front perspective view of the socket assembly; and,
FIG. 9 is a second front view of the socket assembly.
The broken line showing of the socket assembly is for illustrative purposes only and forms no part of the claimed design.

1 Claim, 4 Drawing Sheets
